United States Patent Office.

GEORGE W. CLAPPER, OF MARTINSVILLE, INDIANA, ASSIGNEE TO HIMSELF, THOMAS E. DAWSON, JOEL M. JOHNSON, AND A. S. GREGGS.

Letters Patent No. 90,079, dated May 18, 1869.

IMPROVED FEED-REGULATOR FOR MILLSTONES.

The Schedule referred to in these Letters Patent and making part of the same.

To all whom it may concern:

Be it known that I, GEORGE W. CLAPPER, of Martinsville, Morgan county, State of Indiana, have invented a new Improved Mode of Feeding Burrs or Millstones; and I do hereby declare that the following is a full and exact description of the construction and operation of the same, reference being had to the accompanying drawings, making part of this specification, in which—

Figure 1 represents a vertical longitudinal section of my apparatus, and

Figure 2 represents a top view of the same.

Corresponding letters represent corresponding parts in the two figures.

The nature of my invention consists in providing the runner, or upper millstone with a funnel in the centre of its eye-hole, which branches off into two tubes, bearing on both sides of the rine or cross-bar by which the runner is revolved. The grain is thus conducted to the bed-stone, and equally distributed on the space within the eye-hole, which prevents the stones, or burrs from clogging, this being a general complaint with stones of small diameter revolving at a high speed.

To enable others skilled in the art to make and use my invention, I will proceed to describe its construction and operation.

In the eye-hole B of a runner, or upper millstone, A, represented in part in section, I insert a funnel, or feed-tube, C, which is fastened to said runner, and adjusted concentrically by a number of set-screws, or bolts, D.

These bolts are provided with wings d, or milled heads, to facilitate the turning of them by hand.

The longer ends d¹ of said bolts are pointed, to prevent their slipping against the inner surface of the eye-hole. The shorter ends d², are provided with screw-threads, and are screwed into corresponding sockets e, on the outer surface of the funnel C.

The perforated bottom c¹, rests on top of balance-rine, and is provided with hole c², through which lower end of damsel passes into balance-rine.

At two opposite places in the bottom c¹, there are two segmental openings, to which two segmental conductors E are fastened. They are vertical tubes, and intersect the inclined or conical wall of the funnel C at a considerable height, thereby presenting a very large space at the opening into the funnel.

The object of this is to give the least possible chance to the grain for stopping up the passage into said conductors.

The conductors pass down, and bear on either side of the rine or cross-bar, so as to be steadied thereby.

When the funnel is to be inserted into the eye-hole B, the set-screws D are screwed into their respective sockets, as far as they will go, which brings their

pointed ends within a circle of smaller diameter than that of the eye-hole B. Now the funnel is put into the eye-hole, so that the conductors will bear on either side of the rine, or cross-bar, and the set-screws D are screwed back with their pointed ends against the inner surface of the eye-hole B, until the funnel C is found to be concentric with the eye-hole and the spindle, which supports the runner, taking care that the points d¹ enter far enough into the substance of the runner, to insure the steady position of C for a desired length of time.

Having thus described the construction of my improved feeding-apparatus, the operation is as follows:

The grain is dropped, by a hopper of ordinary construction, to the bottom of the funnel C, which bottom should be somewhat higher at its centre, to make the grain-slide easily from it.

Thence the conductors receive and guide it to the bed-stone, where they spread it equally while revolving.

As a consequence, the grain is at every part of its circumference affected in the same degree by the air-current which is created by the centrifugal power, causing the air to move away from the centre of the revolving burr.

The grain lying loosely, is easily sucked in between the runner and bed-stone, by the said air-current, and the grinding is performed exactly to the same degree of perfection at every point equidistant from the centre of the burrs.

This cannot be done under all circumstances, without my improved feeding-apparatus, and hence the difficulty in grinding with burrs of small diameter, especially when the grain is damp, in which case the grinding always has to be done very slowly, while I am enabled, with my improvement, to keep the runner at three hundred revolutions a minute, without danger of clogging the burrs or burning the flour, but, on the contrary, furnishing a very excellent quality of flour.

Funnel, or tubes within the eye of the runner, I know to be old, being shown in the patents granted to M. H. Ferguson, September 11, 1860, and to J. Nairn, October 6, 1868; the devices, as shown in said cases, therefore, I do not claim, either separately or in combination; but

What I do claim, and desire to secure by Letters Patent, is—

The adjustable funnel C, with its conductors E E, and perforated bottom c, when fixed within the eye of the runner A, by means of set-screws D, all constructed and arranged to operate substantially as and for the purposes herein set forth.

G. W. CLAPPER.
